UNITED STATES PATENT OFFICE.

JAMES HINCHLIFFE, OF PHILADELPHIA, PENNSYLVANIA, ASSIGNOR OF
ONE-HALF TO JOHN DOBSON AND JAMES DOBSON.

SHEDDING MECHANISM FOR LOOMS.

SPECIFICATION forming part of Letters Patent No. 349,794, dated September 28, 1886.

[Application filed November 10, 1884. Serial No. 147,499. (No model.)

To all whom it may concern:

Be it known that I, JAMES HINCHLIFFE, a subject of the Queen of Great Britain, residing in the city of Philadelphia, in the State of Pennsylvania, have invented certain new and useful Improvements in Shedding Mechanism for Looms, of which the following is a full, clear, and exact description, reference being had to the accompanying drawing, forming a part of this specification.

My invention relates to jack-levers for looms; and it has for its object the production of a uniform and steady motion of the jack, in order that the hook thereof will engage with certainty of action in the lifting and depressing bars to produce the rocking movement of the vertical jack-lever for actuating the heddle-frame. This result is accomplished by the mechanism hereinafter described.

It is unnecessary to an understanding of my invention to describe the construction and operation of a loom, as the general mechanism thereof is well known in the art and found described in numerous Letters Patent—for example United States Letters Patent No. 162,904, granted to George Crompton, dated May 4, 1875.

In the accompanying drawing, B represents a vertical heddle-operating lever pivoted at K, and connected at both ends by cords to appropriate heddle-bars of the loom, and serving to alternately raise and depress said bars. A is a hooked jack pivoted at F to a fixed arm, G, secured to the lever. These parts represent this part of the loom as now constructed. Frequently the hooked jack A fails to catch the lifting and depressing bars at each alternate rise and fall of the same, and so causes irregularity in the operation of the loom. In order to avoid this and cause the hooked jack to act with precision, I fix a horizontal post, C, permanently to the vertical lever B and at right angles therewith, and drill

out a long slot in such post to admit of the free rise and fall in such slot of a guide-rod, D, 45 which at one end is securely fastened to the end of the hooked jack A by being screwed into the same, the upper end of said rod passing through the slot of the horizontal post and capped with a nut to prevent the rod from 50 falling through said slot, the latter being long enough to allow the rod to have free play therein in the direction of the length of the hooked jack, and around the said rod, between the hooked jack A and the post C, is wound a 55 spiral spring, E, pressing outwardly between the lower side of the horizontal post C and the upper side of the hooked jack A. The result of this arrangement is, that each movement of the hooked jack is full, precise, and 60 certain, the guide-rod causing it to move always in the same plane, and the spring E by its reflex action after each rising movement of the rod therein causes the said hooked jack A to move freely on the pivot F, and brings it 65 into such position that its hook catches with certainty.

Having thus described my invention, what I claim as new, and desire to secure by Letters Patent, is—

The combination, with the lever-bar B, having a fixed arm, G, and a hooked jack, A, pivoted thereto, of a slotted horizontal post, C, secured to said lever-bar, and a vertical guide-rod, D, secured to said jack A, and reciprocated thereby in the slot of the post C, and a spring, E, encircling said rod D between said post C and jack A, said parts being constructed, combined, and arranged substantially as described.

In testimony whereof I have hereunto affixed my signature this 6th day of November, A. D. 1884.

JAMES HINCHLIFFE.
